UNITED STATES PATENT OFFICE.

WILLIAM C. ROBINSON, OF PITTSBURG, PENNSYLVANIA.

FEED MECHANISM FOR FURNACES.

No. 914,188.

Specification of Letters Patent. Patented March 2, 1909.

Application filed November 27, 1908. Serial No. 464,544.

To all whom it may concern:

Be it known that I, WILLIAM C. ROBINSON, residing at Pittsburg, in the county of Allegheny and State of Pennsylvania, a citizen of the United States, have invented or discovered a certain new and useful Improvement in Feed Mechanism for Furnaces, of which improvement the following is a specification.

The invention described herein has for its object the provision of means whereby a drum or cylinder containing articles to be subjected to heat in the presence of a treating material, can be moved into and out of the furnace and axially rotated while in the furnace to insure the uniform heating of the contents.

The invention is hereinafter more fully described and claimed.

In the accompanying drawings forming a part of this specification Figure 1 is a sectional elevation of a furnace and a portion of the cooling chamber having my improvement applied thereto, Fig. 2 is a similar view of a portion of the furnace and the cooling chamber, Fig. 3 is a transverse section in a plane indicated by the line III—III Fig. 2, Fig. 4 is a sectional plan view; Fig. 5 is a transverse section on a plane indicated by the line V—V Fig. 1. Figs. 6 and 7 are sectional and plan views of the means employed for holding the sprocket chain in engagement of the teeth on the cylinder or drums.

In the practice of my invention a furnace having a heating chamber of a sufficient length to contain a number of drums and preferably having receiving and discharging openings is employed. A plurality of cylinder or drum-carrying chains 1 are passed through the openings at the front and rear of the furnace and around sprocket wheels 2 and 3 on shafts 4 and 5 which are mounted in suitable bearings. The returning portions of the chains pass under the floor of the heating chamber. As shown in Fig. 1 the chains are provided with rollers 6 arranged at the junctions of the links forming the chains and preferably loosely mounted on pins 7 passing through the ends of adjacent links. The rollers move along the rails 8 preferably arranged below the floor of the furnace so that the chains will be largely protected. The links are provided preferably at points midway of their length with rollers 9 loosely mounted on pins 10 secured at their ends to the bars forming the links in such manner

that portions of the rollers 9 will project above the edges of the links. The rollers are so spaced that adjacent rollers will form rotatable supports for the cylinders or drums, which preferably are placed when charged on the skids 11 at the front end of the furnace. These skids preferably have a slight inclination so that the loaded drum will roll down and being seated on adjacent rollers 9 will be carried through the furnace by the chains. While on the furnace the drums are rotated on their axis by means hereinafter described, and in order that the drums may not move longitudinally while rotating on the rollers the latter are grooved for the reception of peripheral ribs 12 on the drums.

The rotation of the drums may be effected by any suitable means such for example as the sprocket chains 13 engaging teeth 14 on the peripheries of the drums. As shown the chain passes around sprocket wheels 15 and 16 loosely mounted on the shafts 4 and 5 at the ends of the furnace. The sprocket wheel 16 is adapted to be connected with a gear wheel 17 by means of a clutch 18 said gear wheel being also loosely mounted on the shaft 5 and driven as hereinafter described. This sprocket chain is yieldingly supported in its passage through the furnace to engage the teeth 14 on the drums. Such support is conveniently formed by rollers 19 over which the chain passes and loosely mounted on one end of a series of levers 20 having their opposite ends weighted as clearly shown in Figs. 4, 5, 6 and 7. These levers have their pivotal shafts 21 mounted in the sides of boxes 22 embedded in the bottom of the furnace. The levers and their supports are preferably spaced a distance apart a little greater than the diameters of the drums so as to insure an efficient engagement of the chain with the teeth on the drum.

A convenient means for driving the shaft 5 consists of a motor 23 operatively connected to a shaft 24 having pinions 25 and 26 respectively intermeshing with gear wheels 27 and 17 loosely mounted on the shaft 5. The gear wheel 27 is adapted to be connected to the shaft 5 by a clutch mechanism 28 when it is desired to rotate the sprocket wheels 3 to move the drums into or along the furnace. After a drum or series of drums has been drawn into the furnace, the clutch 28 is thrown out of operation, and the clutch 18 is shifted to connect the gear wheel 17 with the

sprocket wheel 16 whereby the chain 13 is caused to travel and rotate the drum or drums.

After the contents of the drums have been 5 properly treated the clutch 28 is again thrown in so as to move the drums out through the rear door of the furnace and preferably onto skids 29. It will be understood that newly charged drums can be drawn into the furnace 10 at the same time those which have been properly heated are moved out. During the movement of the drums into and out of the furnace, the sprocket chain 13 may be operated. If the rates of movement of the chains 15 1 and 13 are the same there will not be any rotation of the drums, while being shifted, but if the rates of movement are different, the drums will be rotated while being shifted.

In order to hasten the cooling of the drums 20 and their contents the skids 29 are extended from the rear end of the furnace and are inclosed in a tunnel 30 having a stack 31 at the end adjacent to the furnace and provided with a door 32 at its opposite end for the removal of the drums. A tube 33, arranged adjacent to the discharge end of the tunnel, is connected to a suitable source of fluid under pressure, which will escape into the tunnel through perforations in the tube 33 and 30 flow forward above and below the drums resting on the skids and effect a rapid cooling of the same. As shown the skids are given an inclination so that the drums will roll towards the discharge end of the tunnel and 35 movable stops 34 and 35 are provided for arresting the movement of the drums. These stops may be made in the form of pivotally mounted arms connected at their lower ends to operating rods 36 and 37 extending out 40 side of the tunnel.

I claim herein as my invention:

1. A furnace having in combination there-with endless chains passing through the furnace, means for shifting said chains and rollers 45 rotatably mounted on the chains, and so arranged relative to each other, that adjacent rollers will form supports permitting of the movement of the article being heated independent of its movement through the furnace.

2. A furnace having in combination there-with endless chains passing through the furnace, rollers suitably arranged along said

chains to form movable supports for the article to be heated, means for shifting said 55 chains, and means for rotating the article on the rollers.

3. A furnace having in combination there-with rails extending through the furnace, endless chains provided with rollers adapted to 60 travel along said rails, rollers suitably arranged along the chains to form movable supports for the article to be heated, means for shifting the chains, and means for rotating the article on the rollers. 65

4. A furnace having in combination there-with chains passing through the furnace, means for shifting the chains, rollers suitably arranged along the chains, a drum or cylinder supported by said rollers and provided with 70 teeth arranged around its periphery, an endless sprocket chain passing through the furnace, yielding means for holding said chain in engagement with the teeth on the drum and means for shifting the chain. 75

5. A furnace having in combination there-with endless chains passing through the furnace, rollers suitably arranged along the chains, a drum or cylinder supported by said rollers and provided with teeth arranged 80 around its periphery, an endless sprocket chain passing through the furnace, weighted levers provided with rollers for holding the chain in engagement with the teeth on the drum and means for shifting the chain. 85

6. A furnace having in combination there-with loosely mounted rollers, a drum or cylinder supported by the rollers and provided with teeth arranged around its periphery, a sprocket chain passing through the furnace, 90 yielding means for holding the chain in engagement with the teeth on the drum, and means for shifting the chain.

7. A furnace having in combination there-with a drum or cylinder for the articles to be 95 treated, means for moving the drum through the furnace, means for rotating the drum, a tunnel provided with skids arranged at the discharge end of the furnace, and means for forcing a cooling fluid through said tunnel. 100

In testimony whereof, I have hereunto set my hand.

WILLIAM C. ROBINSON.
